G. H. ROLFES,
BAIL HOLDER FOR LANTERNS.
APPLICATION FILED JUNE 20, 1921.

1,405,007.

Patented Jan. 31, 1922.

Inventor:

G. H. Rolfes
or Cook & McCaulay Assoc.

UNITED STATES PATENT OFFICE.

GEORGE H. ROLFES, OF ST. LOUIS, MISSOURI, ASSIGNOR TO HANDLAN-BUCK MANUFACTURING COMPANY, OF ST. LOUIS, MISSOURI, A CORPORATION OF MISSOURI.

BAIL HOLDER FOR LANTERNS.

1,405,007.

Specification of Letters Patent. Patented Jan. 31, 1922.

Application filed June 20, 1921. Serial No. 478,886.

To all whom it may concern:

Be it known that I, GEORGE H. ROLFES, a citizen of the United States of America, and a resident of the city of St. Louis and 5 State of Missouri, have invented certain new and useful Improvements in Bail Holders for Lanterns, of which the following is a full, clear, and exact description, reference being had to the accompanying drawings, forming a part of this specification.

This invention relates to improvements in bail-holders for lanterns, the main object being to produce a very strong and simple device of this kind whereby a pivotally 15 mounted bail can be very rigidly and securely held to prevent movement of the bail relative to the body of the lantern.

Fig. I is a side elevation showing certain elements of a lantern equipped with a 20 bail holder embodying the features of this invention.

Fig. II is a fragmentary view showing the bail holder applied to the bail.

Fig. III is a vertical section showing the 25 elements illustrated in Fig. II.

Fig. IV is a perspective view of the bail holder.

Fig. V is an enlarged horizontal section taken approximately on the line V—V in 30 Fig. III.

The body of the lantern comprises a hood A mounted on a frame including guard wires 1 and 1', the wires 1 having outwardly 35 extending loops, or eyes, 2 adapted to receive the lower ends of a bail B, the lower ends of said bail having eyes 3 cooperating with the eyes 2 so as to pivotally connect the bail to the frame.

The lantern frame also includes a guard 40 wire 4 surrounding the wires 1 and 1' at points immediately below the eyes 2, and the top wire 5 located within the lower margin of the hood A. The upper ends of the wires 1 and 1' are provided with hooks 6 adapted to receive the top wire 5 as shown 45 in Figs. I and III.

As an illustration of the invention I have shown a bail-holder comprising a single strip of sheet metal bent to provide a fold 50 7, and upper and lower arms 8 and 9 extending from said fold.

The fold 7 is provided with a bail-receiving slot 10 extending into the adjoining ends of the upper and lower arms 8 and 9, 55 as shown most clearly by Figs. III and IV,

said bail-receiving slot being open at the fold to receive the bail, and the adjoining ends of said upper and lower arms 8 and 9 being separated from each other to engage different portions of the bail. The 60 arms 8 and 9 are thus bifurcated to receive the bail.

At the ends remote from the fold 7, the arms 8 and 9 are separated from each other to engage different portions of the lantern 65 frame, the upper arm 8 being provided with an eye 11 surrounding the top wire 5 to provide a pivotal connection between the bail holder and the lantern frame. A slot 12 is formed across the eye 11 and this slot 70 extends into the arm 8 so as to receive the adjacent guard wire 1, the latter being straddled by and engaged with the legs at opposite sides of the slot 12.

A slot 13 is formed in the lower end of 75 arm 9 to receive a portion of the guard wire 1 which is straddled by the slotted end of arm 8. The slot 13 is offset, as shown most clearly in Fig. V, to provide a detent 13' adapted to engage guard wire 1 to latch the 80 pivoted bail holder in its operative position.

The bail holder herein shown may be made of a single piece of sheet metal, and its various elements are so combined with 85 each other and with the lantern frame, that they provide a very strong device for locking the bail. The arms 8 and 9 are separated from each other to engage different 90 portions of the bail, so the latter is securely held at separate points adjacent to the fold 7.

The bail holder itself is securely attached to the lantern through the medium of the pivot eye 11 surrounding the top wire 5, 95 this end of arm 8 being slotted to straddle and engage the adjacent guard wire 1. To firmly secure the bail holder at different points on the lantern frame, the lower end of arm 9 is separated from arm 8, as previously pointed out, and this lower end is slotted to straddle and engage a guard wire 1 at a point some distance below the arm 8.

When the bail holder is not in service, it occupies the position shown by dotted lines 105 in Fig. III. To lock the bail it is only necessary to shift the bail holder from the last mentioned position to the position shown by full lines in Fig. III, and the detent 13' (Figs. IV and V) will then co- 110

operate with a guard wire 1 to lock the bail holder in its operative position.

I claim:

1. A lantern having a body including a frame, a bail pivoted to said body, and a bail-holder comprising a pair of bail engaging arms and a fold uniting said arms, said fold and the adjoining ends of said arms being bifurcated to receive portions of said bail, the other ends of said arms being separated from each other to engage different portions of said frame, one of the last mentioned ends being pivotally connected to said frame and the other being bifurcated 10 to embrace a portion of said frame.
2. A lantern having a body including a frame, a bail pivoted to said body, and a bail-holder comprising a pair of arms each having a bifurcated end to receive said bail, 20 the bifurcated ends of said arms being separated from each other to embrace and engage different portions of the bail, the other ends of said arms being separated from each other to engage different portions of said body, one of the last mentioned ends being 25 pivoted to said frame and the other being provided with a detent adapted to interlock with said frame.

3. A lantern having a body including a frame, a bail pivoted to said body, and a bail-holder comprising a pair of arms each having a bifurcated end to receive said bail, the bifurcated ends of said arms being separated from each other to embrace and engage different portions of the bail, the other ends of said arms being separated from each other to engage different portions of said body, one of the last mentioned ends having 35 a slot for the reception of a portion of said frame and the other having a pivot eye embracing one of the members of said frame and a slot extending from said pivot eye to receive another member of said frame.

4. A lantern having a frame, a bail pivoted to said frame, and a bail-holder in the form of a loop having a fold and bail-engaging arms connected by and extending from said fold, said loop having a bail-receiving slot open at the fold and extending 45 into the adjoining ends of said arms, said adjoining ends of the arms being sep-

arated from each other to embrace different portions of the bail, the other ends of said arms being separated from each other and provided with slots to receive different portions of said frame, and one of the last mentioned ends being pivoted to said frame. 55

5. A lantern having a frame, a bail pivoted to said frame, and a bail-holder comprising a single strip of metal having 60 a fold and upper and lower bail-engaging arms connected by and extending from said fold, said fold being provided with a bail-receiving slot extending into the adjoining ends of said upper and lower arms, said 65 bail-receiving slot being open at the fold to receive the bail, and the adjoining ends of said upper and lower arms being separated from each other to engage different portions of the bail, the other ends of said upper and lower arms being separated from each other to engage different portions of said frame, one of the last mentioned ends being bifurcated 70 to receive a portion of said frame and the other being provided with a pivot eye 75 whereby it is pivoted to another portion of said frame.

6. A lantern having a frame, a bail pivoted to said frame, and a bail-holder comprising a single strip of metal having 80 a fold and upper and lower bail-engaging arms connected by and extending from said fold, said fold being provided with a bail-receiving slot extending into the adjoining ends of said upper and lower arms, said 85 bail-receiving slot being open at the fold to receive the bail, and the adjoining ends of said upper and lower arms being separated from each other to engage different portions of the bail, the other ends of said upper and lower arms being separated from each other and provided with slots to receive different 90 portions of said frame, the last mentioned end of the upper arm having an eye whereby it is pivoted to said frame, and the slot in 95 the last mentioned end of the lower arm being offset to provide a detent whereby the bail-holder is held in its operative position.

In testimony that I claim the foregoing I hereunto affix my signature.

GEORGE H. ROLFES.
